UNITED STATES PATENT OFFICE.

BERNIE E. LEONARD, OF ODEBOLT, IOWA.

FOLDING COAT-HANGER.

1,047,094.

Specification of Letters Patent. Patented Dec. 10, 1912.

Application filed August 2, 1912. Serial No. 712,946.

To all whom it may concern:

Be it known that I, BERNIE E. LEONARD, a citizen of the United States, residing at Odebolt, in the county of Sac, State of Iowa, 5 have invented certain new and useful Improvements in Folding Coat-Hangers; and I do hereby declare the following to be a full, clear, and exact description of the invention, such as will enable others skilled in 10 the art to which it appertains to make and use the same.

This invention relates to folding coat-hangers and has for an object to provide a coat hanger of this character having a pair 15 of novel props which are hinged at their outer ends to the related halves of the hanger and lie snugly within recesses formed in the inner faces of the halves when the coat hanger is folded, but gravitate automatically to operative position upon 20 unfolding of the coat hanger and serve to hold the halves spread apart to operative position.

With the above objects in view the invention 25 consists of certain novel details of construction and combination of parts hereinafter fully described and claimed, it being understood that various modifications may be made in the minor details of construction 30 within the scope of the appended claim.

In the accompanying drawing forming part of this specification:—Figure 1 is a front elevation of the coat hanger in operative position. Fig. 2 is a front elevation of 35 the coat hanger in folded position. Fig. 3 is a cross sectional view taken on the line 3—3 Fig. 1. Fig. 4 is a cross sectional view taken on the line 4—4 Fig. 2.

Referring now to the drawing in which 40 like characters of reference designate similar parts, 10 designates in general a coat hanger arch comprised of two similar halves 11 hingedly connected together at their inner ends by a hinge 12. Each half is provided 45 on the inner face with a longitudinal recess

13. A pair of props 14 are hingedly connected at their outer ends by hinges 15, the props being adapted to fold into the recesses 13 as shown in Fig. 2. The extreme outer ends of the prop are beveled as shown 50 at 16. Upon the props gravitating to alined position when the halves of the arch are opened, the beveled ends contact with the related halves and limit gravitating movement of the props. 55

The extreme inner ends of the props contact one with the other when the props are in operative position as shown in Fig. 1 and prevent folding movement of the halves of the arch. To fold the coat hanger it is simply necessary to manually press both props into their respective recesses, and then fold the halves toward each other as shown in Fig. 2. A supporting hook 17 is secured to one of the halves of the arch and forms 65 means for suspending the coat hanger.

What is claimed, is:—

A folding coat hanger including an arch comprising two similar halves hingedly connected together at their inner ends, each 70 arch having a longitudinal recess in the inner face, and a pair of props hingedly connected at the outer ends to the free ends of said halves and adapted to gravitate to alined position and contact at their inner 75 ends to hold said halves in open position, the extreme outer ends of said props being beveled to form stop faces adapted to contact with the inner faces of said halves and limit gravitating movement of said prop, 80 said props being adapted to fold bodily into said recesses upon said halves being folded toward each other.

In testimony whereof, I affix my signature, in presence of two witnesses.

BERNIE E. LEONARD.
